United States Patent [19]

Wilhelmsen

[11] Patent Number: Des. 317,898

[45] Date of Patent: ** Jul. 2, 1991

[54] REPLACEABLE RESISTOR FOR A
SOLDERING IRON

[75] Inventor: Jack L. Wilhelmsen, Cheraw, S.C.

[73] Assignee: Cooper Industries, Inc., Houston,
Tex.

[**] Term: 14 Years

[21] Appl. No.: 29,472

[22] Filed: Mar. 23, 1987

[52] U.S. Cl. D13/125

[58] Field of Search D13/21, 99; 219/141;
338/258, 279, 314

[57] CLAIM

The ornamental design for a replaceable resistor for a soldering iron, as shown and described.

DESCRIPTION

FIG. 1 is a perspective view of my new design for replaceable resistor for a soldering iron;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof; and

FIG. 7 is a bottom plan view thereof.

FIG. 1

FIG. 2

FIG. 4

FIG. 3

FIG. 5

FIG. 6

FIG. 7
